CLAIM

The ornamental design for a faceplate, as shown and described.

DESCRIPTION

FIG. 1 is a front perspective view of a faceplate showing our new design;

FIG. 2 is a front elevational view thereof;

FIG. 3 is a side elevational view thereof, the opposite side is a mirror image; and,

FIG. 4 is a top plan view thereof, the bottom is a mirror image.

The broken line showing of the plug receiving apertures in FIGS. 1 and 2 is for illustrative purposes only and forms no part of the claimed design.
